SAFE PROTECTIVE APPARATUS

Filed Dec. 11, 1930

Attorney

UNITED STATES PATENT OFFICE

JOHN W. YOUNG, OF PITTSBURGH, PENNSYLVANIA

SAFE PROTECTIVE APPARATUS

Application filed December 11, 1930. Serial No. 501,635.

This invention relates to protective apparatus for vaults, safes and similar depositories, more particularly it is directed to an installation adapted to be associated with the doors of such depositories to the end that any attempt to gain access thereto other than through the operation of the combination mechanism will liberate a gas capable of temporarily incapacitating the intruder and at the same time effect actuation of an auxiliary bolt mechanism.

One of the objects of this invention is to provide an installation of the character indicated by means of which the pressure of the temporarily incapacitating agent is utilized for the purpose of throwing one or more auxiliary locking bolts into operative position.

Another object of this invention is to provide a gas disbursing and auxiliary locking device applicable to the interior of safes, vaults and the like, having facilities for accomplishing through a single instrumentality, namely, the temporarily incapacitating agent, that which heretofore required not only the gas, but likewise a mechanical arrangement for releasing and throwing the auxiliary bolts into operative position.

Another object of this invention is to effect a gas operative, an auxiliary bolt construction having gas outlet ports permitting the gas after it has thrown the bolts, to escape to the interior of the safe for the purpose of incapacitating the person unlawfully seeking access to the safe, vault or the like.

Another object of this invention is to provide a device of the type indicated which will insure a release of the gas and operation of the bolts when but a single tension cord has been severed in the attempt to gain access to the safe.

Another object of this invention is to provide a gas protective apparatus and auxiliary locking mechanism which may be readily applied to safe doors or the like at the time of manufacture or to existing structures with a minimum expenditure of time, labor and material, and to furnish a gas liberating and auxiliary lock installation embodying but few parts instantly effective to release a gas of

a temporarily incapacitating nature and operating one or more bolts should the safe door be unlawfully tampered with.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a fragmentary sectionized view partly in elevation illustrating the installation constituting the subject matter of this application as applied to the usual form of safe doors.

Fig. 2 is a detailed fragmentary sectionized view partly in elevation of the generator ignition means and one of the auxiliary locking devices.

Fig. 3 is a sectionized detail partly in elevation of the bearing block and associated parts.

Fig. 4 is a transfer vertical taken on the line 4-4 of Fig. 3; and

Fig. 5 is a detailed horizontal section partly in elevation of the generator and associated parts.

In my pending application, Serial No. 444,498, filed April 15, 1930, title safe protective apparatus, there is described a gas protective apparatus consisting of a generator adapted to contain a substance capable of producing a gas of a temporarily incapacitating nature and a combustible charge to expell the gas under pressure, the generator being mounted on the rear wall of the safe door, a normally inoperative ignition means in connection with the generator to fire the combustible mixture and an ignition releasing mechanism automatically functioning to render the ignition operative upon an attempted removal of the front plate of the safe, vault or similar depository.

In effecting the improvement constituting the subject matter of this application, the same subject matter is utilized as described in the application hereinabove defined with the addition of an auxiliary locking mechanism, the latter being operated by the pres-

sure of the combustible charge used for expelling the temporarily incapacitating agent, or by the agent itself dependent upon the exigency of the situation.

6 In the illustrated embodiment characterizing this invention, A represents the door of a safe, vault or other depositories; B and C, its front and rear plates, respectively, which are attached in the usual manner to a supporting frame D. The main bolt of the door (not shown) is controlled by the customary combination mechanism.

10 To produce the requisite temporarily incapacitating agent, there is provided a generator H consisting of a metallic container divided into compartments F and G by the central partition 1. This container is adapted to be bolted or otherwise attached to the rear plate of the safe door, and has its top portion formed with two lateral spaced aligned openings 2 and 3 respectively, each of which is surrounded by a vertically disposed sleeve 4. The lower ends of these sleeves project to a slight extent into the interior of the respective compartments as clearly shown in Fig. 2 of the drawings, while the upper ends thereof are closed by plugs 4', the latter being centrally formed with suitable openings to slidably receive firing pins 5 and 5' adapted to cooperate with detonators 6 positioned in the lower ends of the sleeves. Firing pin 5 is normally held in unarmed position with respect to detonator 6, against the action of a spring 7 by means of a shearable tension cord 8.

15 The compartments F and G of the container are each charged with a combustible mixture and a substance for producing a gas of a temporarily incapacitating nature, the combustible mixture functioning upon ignition as a propellant to force the toxic agent to the exterior of the generator.

20 To effect release of firing pin 5 associated with compartment F when the front plate of the door is tampered with, the upper end of said firing pin is connected to a shearable tension cord 8 which extends upwardly from the firing pin and passes through a slot 9 in a bearing block 10 mounted adjacent the upper end of the rear plate C. The free end of cord 8 is attached to an anchoring pin 11 projecting from the rear plate C above bearing block 10 as clearly shown in Fig. 1 of the drawings.

25 Bearing block 10 is interiorly formed with an annular opening 12 in which is slidably positioned a similarly shaped shearing head 13, said head being formed with a peripheral groove 14 tangentially disposed with respect to the slot 9 in block 10 so that cord 8 in passing through slot 9 also extends between the walls of groove 14 as clearly shown in Fig. 4 of the drawings. Shearing head 13 is affixed to the inner end of a rod 15 which extends transversely through the interior of the door

30 from block 10 to the front plate B and terminates with its free end flush with the outer surface of plate B. In this connection it is to be understood the attachment of the free end of rod 15 to the front plate of the safe door must be carefully made for concealment purposes since detection of the connection might seriously impair the effectiveness of the invention.

35 With the parts assembled as just described, it will be evident removal of the front plate B of the safe door retracts head 13 of block 10 and as the latter moves outwardly from its seat, owing to the engagement of the walls of groove 14 with tension cord 8, said cord will be sheared permitting firing pin 5 under the action of its spring 7 to strike and fire detonator 6 thereby igniting the combustible mixture in compartment F and propelling the temporarily incapacitating agent therein to the exterior of said generator as will herein-after appear.

40 Firing pin 5' is retained in unarmed position with respect to detonator 6 by means of a horizontally disposed lever 16 pivoted at 90 one end as at 17 to bracket 18 affixed to the sleeve 4 of firing pin 5 as clearly shown in Figs. 1 and 2 of the drawings. The free portion of lever 16 extends through a slot 19 formed in the upper end of firing pin 5 and to the combination mechanism E to which it is attached as at 16'.

45 By this arrangement, any attempt to enter the safe through the combination housing will disengage the lever 16 from its position 100 in slot 19 and permit firing pin 5' under the action of its spring 7 to explode the detonator 6 and ignite the combustible mixture in compartment G with the same result as in the case of firing pin 5.

50 Coming now to the principal feature of this invention, namely, the auxiliary locking mechanism by means of which a pair of suitably locked bolts are thrown into locking or operative position through the instrumentality of the gas produced by the generator prior to its escape there is provided in connection with the respective compartments F and G of the container bolt assembly I and K. Assembly I consists of a tubular sleeve 20, one end of which communicates with the interior of compartment F through the opening 21 formed adjacent the upper end of said compartment while the opposite end of said sleeve opens into bolt seat 22 formed in one of the side members of the door and frames A and D, respectively, as clearly shown in Figs. 1 and 2 of the drawings.

55 In order to permit escape of the gas developed in compartment F upon ignition of the combustible mixture, sleeve 20 is formed with an outlet port 23. Normally this port is closed by the tubular bolt 24 slidably positioned in sleeve 20 since the bolt in its re-

tracted position overlies the port. When the bolt under the pressure of the gas has been thrown into locking position, that is to say with its outer end projecting into seat 22, 5 port 23 is opened, thus venting the gas to the exterior of the container. A spring actuated detent 25 pivoted to the undersurface of sleeve 20 as at 26 is adapted to project through opening 27 through sleeve 20 and into notch 10 28 formed in the inner end of the bolt for the purpose of locking the latter in its operative position.

With the components of locking mechanism I associated as hereinabove stated, it 15 will be manifest upon explosion of detonator 6 in compartment F, the pressure of the ensuring gases of combustion will first throw the bolt 24 into locking position and then upon uncovering of port 23, escape to the 20 exterior atmosphere.

Bolt assembly K is identical with assembly I in that it embodies sleeve 20', bolt seat 22', port 23', slideable bolt 24', spring actuated detent 25', and its associated parts. In this 25 assembly, however, the free end of the sleeve is not connected directly with compartment G of the container but communicates with the interior of said compartment by means of a tube 29 as clearly shown in Figure 1 of 30 the drawings.

In the light of the preceding structural detail, it will be seen that an attempted removal of the front plate of the safe door will result in severance of tension cord 8, release 35 of firing pin 5, and explosion of detonator 6 in compartment F of the container, with consequent ignition of the combustible mixture therein, the pressure of which forces bolt 24 to locking position and opens port 23, thus 40 permitting escape of the products of combustion together with the temporarily incapacitating agent. On the other hand, if the combination mechanism is tampered with, lever 16 will be removed from its seat in firing pin 45 5' thereby releasing said pin and exploding detonator cap 6 in compartment G, whereupon the gas developed therein passing through tube 29 actuates bolt 24 to locking position and then escapes through port 23' as will be 55 readily understood without further discussion.

In conclusion it is apparent this invention furnishes an auxiliary locking mechanism which may be operated by means of the temporarily incapacitating agent preliminary to its liberation, thus eliminating the various bolt actuating devices hereto employed for actuation of the auxiliary bolts concomitant with the release of the temporarily incapacitating agent.

Having thus described my invention, what I desire protected by Letters Patent is as set forth in the following claims:

1. A safe protective apparatus comprising an auxiliary locking mechanism including a

gas chamber and a bolt slideable in the chamber, said bolt being normally retained in inoperative position but operable to an operative position by the gas entering said chamber, means for supplying a gas of a temporarily incapacitating nature to said chamber, and means for effecting release of the gas for incapacitating purposes, as the bolt is actuated to operative position. 70

2. A safe protective apparatus comprising 75 an auxiliary locking device including a gas chamber and a slideable bolt normally held in inoperative position but adapted to be actuated to operative position by the gas entering said chamber, means for supplying a gas of a temporarily incapacitating nature to said chamber, and additional means in connection with said chamber to release the gas for incapacitating purposes, said means being controlled by the movement of the bolt. 80

3. A safe protective apparatus comprising 85 an auxiliary locking mechanism, including a gas chamber and a slideable bolt normally maintained in operative position and adapted to be operated by the gas entering said chamber, means for supplying gas of a temporarily incapacitating nature to said chamber, and means for releasing said gas from the chamber for incapacitating purposes, said means including an aperture adapted to be uncovered 90 by the movement of the bolt. 95

4. A safe protective apparatus comprising 100 an auxiliary locking mechanism, including a gas chamber, a slideable bolt normally maintained in operative position and adapted to be operated by the gas entering said chamber, a gas generating device for producing gas of a temporarily incapacitating nature, means for setting said device into operation, a conduit connecting said gas generating device 105 with said chamber, and means in connection with said chamber to release the gas for incapacitating purposes as the bolt is actuated to operative position.

5. A safe protective apparatus comprising 110 an auxiliary locking mechanism, including a gas chamber, and a slideable bolt normally retained in inoperative position and adapted to be moved to operative position by the gas entering said chamber, a gas generating device 115 for producing gas of a temporarily incapacitating nature, means for setting said device into operation, a conduit connecting said gas generating device to said chamber, and means in connection with said chamber and controlled by the movement of the bolt to release the gas for incapacitating purposes, said means including an aperture adapted to be uncovered as the bolt is actuated to operative position. 120 125
